ORNAMENTAL BACKING PLATE FOR HANDLE
AS USED ON DOORS, DRAWERS, AND THE LIKE

David F. James, Redondo Beach, Calif., assignor to Hyer
Hardware Mfg. Co., Anaheim, Calif.

Filed Sept. 10, 1971, Ser. No. 179,607

Term of patent 14 years

Int. Cl. D8—09

U.S. Cl. D8—179

FIG. 1.

FIG. 2.

FIG. 3.

FIG. 4.

FIG. 1 is a perspective view of an ornamental backing plate for handles as used on doors, drawers, and the like, showing my new design;

FIG. 2 is a face view thereof;

FIG. 3 is an elevational view of one of the similar side edges thereof; and

FIG. 4 is an elevational view of one of the similar ends thereof.

I claim:

The ornamental design for an ornamental backing plate for handle as used on doors, drawers, and the like, as shown.
